Filed Mar. 22, 1963, Ser. No. 74,089

Term of patent 14 years

(Cl. D13—1)

Fig. 1

The rear of the carport is identical to the front as seen in FIGURE 1 and the side opposite the side shown in FIGURE 2 is identical thereto.

I claim:

The ornamental design for a portable carport or the like, as shown and described.
